UNITED STATES PATENT OFFICE.

GEORGE P. BRAND, OF NEW YORK, N. Y.

TRACKING DEVICE FOR PLAYER PIANOS.

1,422,824.

Specification of Letters Patent. Patented July 18, 1922.

Application filed October 25, 1917. Serial No. 198,468.

To all whom it may concern:

Be it known that I, GEORGE P. BRAND, a citizen of the United States, residing at the city of New York, borough of Bronx, in the county of Bronx and State of New York, have invented certain new and useful Improvements in Tracking Devices for Player Pianos, of which the following is a specification.

10 This invention is a tracking device for player pianos, and relates, more particularly, to pianos of that character wherein the actions are controlled by a perforated music sheet passing over a tracker bar containing 15 air ducts equal in number to the number of actions.

The principal object of all inventions of this character is to insure proper lateral alinement or registration between the perforations in the music sheet and the air ducts of the tracker bar, while the main difficulty to be overcome is varying widths in the music sheet brought about through imperfect cutting thereof or unevennesses resulting from warping, stretching, or expansion and contraction of the paper from which the sheets are generally made, under the influence of climatic conditions. These deleterious conditions all tend to seriously 30 affect the lateral alinement between the tracker ducts and music sheet openings, and great difficulty has been encountered in obtaining a tracker device which will so control the relation between the music sheet and 35 tracker bar as to maintain proper alinement at all times and adequately guard against any and all of the foregoing deleterious conditions.

The most successful tracking devices thus far produced are those which are pneumatically controlled and operate to bring about relative lateral adjustment between the tracker bar and the music sheet. This pneumatic control has generally been dependent 45 for its operation upon the relative position between one edge of the music sheet and air ducts in the tracker bar. So long as the music sheet is in proper position, it serves to seal the ducts in question, but when it 50 moves laterally out of adjustment, one of the ducts is uncovered and air is allowed to pass to the pneumatic controller, which operates to return the sheet to correct position.

55 The chief disadvantage in devices of this character is due to the fact that the pneu-

matic controller does not actually maintain the music sheet in proper lateral adjustment, but comes into operation only after the sheet is out of adjustment, for the purpose of returning it to correct position. This is because of the fact that the music sheet must move sufficiently away from its true path to uncover one of the ducts before the pneumatic controller can be brought into operation. With music sheets of different widths, such as those made by different manufacturers, the pneumatic control, depending upon the uncovering of ducts in the tracker bar, is practically inoperative. This is due to the fact that uniform sheet widths are required to obtain the adjustment desired.

Another disadvantage inherent in pneumatically controlled tracker devices of the character described, as well as others, is that there is always considerable leakage, which makes it practically impossible to obtain constant or uniform air pressure. In the absence of uniform pressure, the controlling means cannot possibly operate in a uniform manner. In all prior tracking devices, the lateral adjustment between the tracker bar and the music sheet is dependent upon air pressure which should be constant or uniform, and, since such uniformity is practically impossible, the maintenance of the perforations of the music sheet at all times in absolute registration with the action controlling air ducts in the tracker bar, is not obtained.

Furthermore, pneumatically operating devices operate relatively slow, so that a defective music sheet, having an uneven edge, will not produce a quick enough response by the pneumatic controlling means to compensate for the varying contour of the edge, and said sheet will get out of adjustment, and stay out of adjustment until a smoother portion of the edge of the sheet is reached. This last mentioned difficulty is encountered in all pneumatically controlled tracking devices which depend for their operation upon means adapted to rest against the edge of the music sheet during the playing operation.

With the foregoing considerations in mind, the objects of the present invention are to provide a purely mechanical tracker, thereby obviating failure of the device to properly operate due to leakage, as heretofore; to provide a purely mechanical tracker which will actually maintain the music sheet

in proper position for correct tracking, and will not require the movement of said sheet out of position before the tracking device becomes operative, as is the case with pneumatic trackers; to provide a mechanical tracker which is extremely sensitive and which will operate with great rapidity, without tearing the music sheet or causing fraying of the edges thereof; and to obtain maximum simplicity in such a structure and one which cannot fail to operate in correcting all imperfections in the music sheet, due either to imperfect manufacture or climatic changes. A further object of the invention is the provision of a tracking device which is automatically adjustable to music sheets of slightly varying widths and will thus bring about proper tracking of any particular instrument when cooperating with music sheets of different makes.

A further salient feature of the invention is to provide a mechanical tracker which will operate perfectly on any music sheet and without requiring any adjustments whatsoever after the tracker has been initially installed and properly adjusted.

In tracker devices as heretofore constructed, it has been necessary for the music sheet to be deflected a clearly perceptible distance from its normal path before it could actuate certain mechanisms for the purpose of returning the sheet to said normal path, and this necessarily meant that the music sheet would be out of alignment for a substantial period of time. The present invention, in contradistinction, does not require that the music sheet be so deflected, but, on the contrary, the very slightest attempt by said sheet to move laterally is sufficient to actuate the tracking means and assure the maintenance of perfect alignment, the result being that there is no misalignment, in the ordinary sense of the term. In this respect, the invention embodies an entirely new principle of operation.

Features of the invention, other than those specified, as well as the advantages thereof, will be apparent from the hereinafter detailed description taken in conjunction with the accompanying drawings.

In the accompanying drawings I have illustrated different practical embodiments of the invention, but the constructions therein shown are to be understood as illustrative, only, and not as defining the limits of the invention.

Figure 1 is a front elevation of the frame of an automatic player piano, on which are mounted the tracker bar, the music feed and take-up rolls, and the conjunctive devices for operating said rolls, in combination with which is shown a tracking device embodying the present invention.

Figure 2 is a horizontal section taken in the plane of the line 2—2 of Figure 1, show-

ing the parts in the positions which they occupy during the playing operation.

Figure 3 is a diagrammatic showing of the tracker parts illustrated in Figure 2, but showing said parts in the positions which they occupy while the roll is being rewound.

Figure 4 is a vertical section in the plane of the line 4—4 of Figure 2.

Figure 5 is a section in the plane of the line 5—5 of Figure 2.

Figure 6 is a section on line 6—6 of Figure 7.

Figure 7 is a plan view of the power parts of the tracking device shown in Figures 1 and 2.

Figure 8 is a view similar to Figure 2, but illustrating a modified and simplified form of tracking means.

Figure 9 is a front elevation of the left hand end of the structure shown in Figure 8.

Figure 10 is a detail end elevation, on a large scale, of the modified form of tracking device shown in Figures 8 and 9, said view being taken as viewed in right angular relation to the plane of the line 10—10 of Figure 8.

Figure 11 is a section on the line 11—11 of Figure 10.

Figure 12 is a detail elevation of certain clutch mechanism which is preferably employed, and

Figure 13 is a section on line 13—13 of Figure 12.

In order that the present invention may be clearly understood, the parts of a player piano with which the tracking device is associated and cooperates are shown in the drawings. These parts embody the usual frame having parallel sides A, A' and a back A², all of which are rigidly mounted within the case of a piano. Substantially midway of the height of the sides A and A', and near the forward edge thereof, are secured the opposite ends of the tracker bar B, and beneath tracker bar B is rotatably mounted the take-up roll C, while above the tracker bar, and extending through the sides A and A', are the two trunnions, D and E, which carry the music roll. Trunnion D is mounted for longitudinal, sliding movement and has associated therewith a spring d for normally advancing said trunnion and forcing the opposite end of the music roll tightly against trunnion E.

Trunnion E is also mounted for longitudinal, sliding movement, as well as for rotary movement, and is provided with an operating stem e which passes through the side A' of the frame and is journaled near its outer end in a bracket F secured by screws f to said side A'. When a music roll is supported on trunnions D and E, in the usual manner, and maintained in engagement with said trunnions by virtue of the springs d, rotary movement may be imparted thereto, as in re-

winding, by means of a sprocket wheel f' fixed on stem e , and with which is associated a sprocket chain f^2 encircling a sprocket g loose on drive shaft G , which is journaled 5 for rotation in bracket F .

At the outer end of shaft G is fixed a prime moving sprocket g' driven from well known mechanism, and slidably mounted on the shaft is the usual clutch g^2 provided with a 10 pin g^3 adapted to cooperate with a pin g^4 on sprocket g , when the clutch is moved in one direction, and having formed thereon a gear g^5 adapted to cooperate with a gear c' , fixed on the shaft c of the take-up roll C , when 15 moved in the other direction.

Clutch g^2 is slid longitudinally of shaft G by means of an arm h fixed on a rock-shaft H journaled in bracket F , and movement to which is imparted by a second arm 20 h' connected with the usual mechanism of the piano for conditioning the mechanism for playing or rewinding, as desired. Shaft G is the prime mover, so that, when the pinion of the clutch g^2 is in engagement with 25 the gear c' , take-up roll C is operated and the music roll drawn across the face of the tracker bar, whereas, when pin g^3 is in engagement with pin g^4 , the music roll mounted on trunnions D and E is directly operated 30 through shaft e and the music sheet is re-wound upon the roll.

The foregoing elements of the construction are well known in the player art and have been described in order that the following detailed description of the mechanism of this invention, as well as the operation thereof, may be clearly understood.

As heretofore stated, trunnion E and stem e are mounted for longitudinal movement, 40 while the spring d of the other trunnion, operating through the music roll, normally tends to force trunnion E outwardly through the side A' . The degree to which such movement of trunnion E is capable is limited by 45 a finger i mounted on the rock-shaft I , which is journaled in lugs on bracket F , and movement of the rock-shaft is controlled through a link J cooperating, at one end, with an arm j fixed to rock-shaft I , and at the other 50 end with either the mechanism shown in detail in Figures 5, 6 and 7, or that shown in Figures 10 and 11, both of which will be hereinafter more fully described. The mechanism in question serves to move the link 55 longitudinally, thereby oscillating finger i in a direction toward or away from trunnion E , and by this operation the music roll is shifted longitudinally and in parallel relation to the tracker bar. It will be understood, 60 that, during this operation, the receding of finger i from the end of stem e will allow spring d to shift the music roll to the right in Figure 1, while the forward movement of said finger will shift the music roll 65 to the left against the tension of spring d .

In this manner, the music sheet will be shifted bodily in a lateral direction relative to the air ducts b in the tracker bar.

I will now proceed to describe the further tracker mechanism shown in Figures 1 to 7, 70 and will, thereafter, set forth in detail that shown in Figures 8 to 13. The mechanism for positively operating link J , in the construction of Figures 1 to 7, is shown in detail in Figures 5, 6 and 7. It embodies a supporting casing K which is supported in spaced relation laterally of the side A on brackets k , as best shown in Figures 1 and 2. Within the side of the casing adjacent the side A is journaled a shaft L which is 80 operatively driven, through sprocket and chain connections l , from the shaft c on which the take-up roll C is mounted. A pawl and ratchet arrangement l' is included in said sprocket and chain connections, so 85 that shaft L will be rotated only when the take-up roll is turned in a direction to wind the music sheet upon the take-up roll, said shaft L remaining idle during the rewinding operation. 90

On shaft L , and interior of casing K , is a friction disk M , with which cooperates a friction wheel M' . Friction wheel M' is mounted on a shaft m journaled at one end in the front wall of casing K and, at its 95 other end, in a swinging hanger m' pivoted on a pin m^2 . On the forward end of shaft m is a pinion m^3 which is connected, through a train of gears m^4 , m^5 , m^6 and m^7 , to a gear n fixed on a shaft N journaled in both the 100 front and back walls of casing K and extending rearwardly beyond the latter. About shaft N is coiled a helical spring N' , one end of which is secured to a collar n' fixed on shaft N , while the other end of said 105 spring is hooked over a pin n^2 projecting forwardly from the back wall of the casing.

With this construction, it will appear that, if friction wheel M' is held tightly against the friction disk M , while the music sheet is being rolled upon the take-up roll, shaft m , on which the friction wheel is mounted, will be rotated and will operate, through the train of gears m^3 to m^7 and gear n , to rotate shaft N in a clockwise direction and place 110 spring N' under tension. On that portion of shaft N which projects beyond the back of casing K is fixed an arm j' , which is pivotally connected to the adjacent end of link J , so that, when shaft N is rotated to place 115 spring N' under tension, arm j' will be simultaneously oscillated to push link J longitudinally and, by so doing, shift arm j on shaft I , as hereinbefore explained. 120

Thus, whenever the music sheet is traveling from the music roll to the take-up roll, spring N' is being placed under tension and link J is being simultaneously shifted to the right in Figure 1. This shifting of the link in the direction specified is limited, to a 130

maximum degree, by means of a stop n^3 fixed on shaft N and adapted to engage with the inclined face n^4 of the bracket in which the rear ends of the shafts of gears m^5 and 5 m^6 are journaled, as clearly shown in Figure 6. As soon as stop n^3 engages with said inclined surface, however, further rotation of shaft N in a clockwise direction will be precluded, and, if friction wheel M' still 10 engages with friction disk M, slipping will occur between said parts. It will thus appear that the operation of winding the music sheet upon the take-up roll will serve, through link J, arm j, and rock shaft I, to 15 retract finger i from the end of the stem e of trunnion E, thereby allowing spring d to move the music sheet laterally to the right in Figure 1, and the tendency will be to maintain the roll in this position until the 20 tight pressure of friction wheel M' against friction disk M is sufficiently lessened to allow of free slipping between the parts, whereupon spring N' will oscillate arm j' in a counter-clockwise direction, drawing link 25 J with it and forcing the music sheet laterally to the left in Figure 1 against the tension of spring d.

There are thus, figuratively speaking, two forces opposing one another, namely, that 30 of the spring d to move the music sheet to the right, and that of spring N' to move it to the left. The force of spring d is always present, whereas spring N' is normally held in check by the tight engagement of friction 35 wheel M' with disk M. The wheel M', however, does not always press tightly against disk M, the degree of pressure being governed by the mechanism next to be described, which mechanism is directly operated or controlled by engagement with the music sheet. 40

The means which cooperates with the music sheet and by which relative positions between friction wheel M' and cooperating disk M are controlled, is best shown in 45 Figures 1 and 2. Two brackets o and o' are mounted on the back of the tracker bar and form supports for two pivoted levers o^2 and o^3 , the forward ends of which levers extend through slots in the tracker bar and are 50 formed into controlling stops or note sheet guide fingers o and o', adapted to engage with the edge of the music sheet X, as shown in Figure 2. Levers o^2 and o^3 are normally maintained in engagement with the opposite 55 edges of the sheet X by means of springs o^4 and o^5 , respectively, secured to said levers and the brackets o and o'.

Mounted on bracket o is a swinging arm p pivoted, at p', to said bracket and carrying near its free end an equalizer lever P pivoted to the swinging arm at a point substantially equidistant from its ends. One end of the equalizer P is connected, through a link p^2 , to the rear end of lever o^2 , while 65 the other end of said equalizer is connected,

through a link p^3 , to the rear end of the other lever o^3 . Through the interposition of equalizer P in the connections between the levers o^2 and o^3 , the movement of the stop O to the left will cause an equidistant movement of the stop O' to the right and will thereby allow of the positioning of music sheets X, of slightly varying widths, between said stops without in the least effecting pivotal movement of the swinging arm 75 p, which will remain stationary owing to the operation of equalizer P. As a matter of fact, the chief function of lever o^2 is to compensate for these varying widths of music sheets, said lever operating through equalizer 80 P to shift stop O' laterally in synchronism with the lateral movement of the stop O, so that both stops are at all times maintained in engagement with the opposite edges of the music sheet. It will be noted, however, 85 that, if the music sheet X moves laterally to the right in Figure 2, the movement transmitted to lever o^3 through stop O' will not be communicated to stop o^2 in the same manner as vice versa, the push on links 90 p^3 and p^2 , opposed by spring o^4 , resulting in the oscillation of the swinging arm p in a counter-clockwise direction. The free end of arm p is connected through links q and q' with the lower end of hanger m' on which 95 is mounted one end of the shaft carrying friction wheel M', so that oscillation of the swinging arm p exerts a thrust, through links q and q', upon friction wheel M', thereby having a tendency to move it free 100 from engagement with friction disk M. Friction wheel M' does not, however, actually leave contact with friction disk M, since, as soon as the pressure which holds said wheel tightly against said disk is released, 105 the wheel immediately slips under the impulse of spring N', thereby causing the feed roll to be moved laterally to the left in Figure 1, or in a direction away from the stop O'. This function results from the fact that, 110 when spring N' is released, it moves link J longitudinally to the right, and, operating through arm j, shaft I, and finger i, moves the music roll, which is carried by trunnions D and E, slightly to the left in 115 Figure 1, against the tension of spring d.

Thus, in practice, friction wheel M' is always in contact with friction disk M. So long as wheel M' is held tightly against the disk, it receives traction therefrom, but, 120 when this pressure is lessened sufficiently to allow spring N' to exert itself, slipping occurs between these parts. Accordingly, as there is no distinct relative movement of wheel M' toward or away from disk M, 125 there is no lost motion, and, since the slightest relaxation of pressure between these parts will allow of the slipping of the friction wheel, the very slightest excess pressure against stop O', brought about by a tendency 130

of the music sheet to move laterally and destroy the alinement, will cause the parts of the tracking device to come into immediate operation and preclude such lateral movement of the music sheet. As the slightest excess pressure against stop O' will bring about this result, the music sheet can never move laterally to destroy the alinement, but is positively maintained at all times in correct position, wherein the alinement will be perfect. The tracking device of this invention is extremely sensitive, and it is due to this fact that the music sheet is never allowed to get out of alinement, but is actually maintained in alinement at all times. In this respect, the present invention is a marked advance over the devices of the prior art, wherein it was required that the music sheet actually leave its correct position in order to operate means, the function of which was to return the sheet to correct position.

Having described the foregoing construction, its operation, in effecting correct tracking, will be apparent to those skilled in the art, since it will appear that, while spring d behind trunnion D normally serves to shift the music roll to the extreme right, as soon as said roll moves far enough in this direction to cause the edge of the music sheet to exert excess pressure on the stop O', the spring N' will be released and the restraining finger i will be acted upon by spring N' to oppose the operation of spring d, i. e., stop the movement of the sheet to the right. The parts are so adjusted during manufacture that this position of the forces will bring the music sheet to rest, with the apertures therein in correct registration or alinement with the air ducts b of the tracker bar. This is the correct tracking position of the music sheet. Accordingly, the slightest tendency of the sheet to deviate laterally from its correct path, during the playing operation, will cause the immediate operation of the correcting devices to preclude such lateral deviation of the sheet and will serve to maintain the sheet in correct tracking position. In practice, the devices operate so quickly that the sheet does not have time to move from correct position before its tendency to move is compensated for or overcome by the tracking device. In this respect, the present invention is, as hereinbefore stated, a marked improvement over prior art devices wherein the sheet was required to become out of adjustment to an appreciable extent before the correcting adjuncts could be brought into operation to return the sheet to proper position.

In practice, absolutely perfect sheets are exceptions, rather than the rule, so that it is found that, in the normal operation of a device embodying this invention, there is a constant operation of the parts. That is to say, the restraining finger i is practically

constantly moving and the pressure between the friction wheel and the friction disk is consequently changing. This is brought about by the slight unevenness in the edge and width of practically all music sheets, 70 coupled with the fact that the tracking device is responsive to the slightest variation and serves to instantly compensate therefor. Thus, as the music sheet travels over the tracker bar and each little variation is met 75 with, the tracking device laterally shifts the sheet, first in one direction and then in the other, to individually compensate for each variation, so that the perforations are always alined and in perfect registration with 80 the air duct b of the tracker bar. When the mechanism is once initially adjusted, it cannot fail to preserve correct registration, i. e., the perforations of the music sheet cannot get out of alinement with the ducts of the 85 tracker bar.

So smoothly does the device operate, however, that, even though it is practically continuously operating, it is noiseless and its presence is not manifest to the operator of 90 the piano. The parts are preferably made quite light, and this applies to the train of gears within casing K. In order that these gears will not be stripped or placed under undue strain when spring N' is released, 95 shaft N has associated therewith a stop r which is adapted to engage with shaft m at the conclusion of the unwinding operation of spring N', which forces friction wheel M' tightly against disk M, thereby braking 100 wheel M' which has been running at high speed during the unwinding operation of the spring, and, by so doing, obviating the necessity of said gears taking up the momentum of the wheel in stopping the same. 105

Although stops O and O' are in engagement with the lateral edges of the music sheet at all times during the playing operation, I find it desirable to have them removed from such contact during the rewinding operation, since, by so doing, unnecessary wear, due to the high speed of the sheet during the rewinding, is obviated. This is accomplished by pivoting a lever S to the bracket o', as shown in Figures 2 and 3, at 110 substantially the center of said lever. One end of the lever is connected by a link s to the arm h which operates the clutch g², while to the other end of said lever is connected a link s' adapted to engage with the lever o², 115 as shown in Figures 2 and 3, the link s' serving as a push link and engaging with the edge of the lever, as shown.

With this construction and arrangement of parts, it will be apparent that, when 125 clutch g² is in a position to drive the gear c', link s' will be retracted to the right and the parts will be in the position shown in Figure 2, to allow of the unrestricted engagement of stops O and O' with the edge of 130

the music sheet. However, if clutch g^2 is moved to cooperate with rewinding gear g , link s' will be forced to the left, thereby imparting similar movement to the stop O , with the result that stop O' will be shifted to the right, the parts taking the positions shown in Figure 3, wherein the stops O and O' are moved away from one another and free from engagement with the edge of the music sheet. The rewinding operation may now take place, with the edges of the sheet entirely unrestricted and unexposed to wear.

Having fully described the details of construction and mode of operation of the embodiment of the invention illustrated in Figures 1 to 7, inclusive, I will now specifically set forth the embodiment of Figures 8 to 13, inclusive. It may be said, in general, that the same broad underlying principle is true of the latter construction as is the case in the former, although, in the latter case, the structure is greatly simplified and is the one which it is preferred to embody in the practical application of the invention.

The structure of Figures 8 to 13 embodies the usual frame having the parallel sides A A' and the back A^2 . At the forward edge thereof is mounted the tracker bar B , with its associated air ducts b . The music roll is supported on trunnions, as heretofore, and the take-up roll C is mounted on the shaft c , which has the sprocket and chain connection l with the shaft L carrying the friction disk M . Shaft c is driven, as hereinbefore described, through the gear c' , clutch mechanism g^3 , and gear g' , and movement is imparted to the music roll through the gear g and chain and sprocket connections, as described with reference to the other construction. The shaft I is provided with the cooperating finger i , which cooperates with the trunnion E carrying the music roll, and said shaft I is operated by the arm j to which is attached one end of the link J , the construction thus far described being substantially the same as that shown in Figures 1 and 2, except that in Figure 8 the arm j is of less length than that shown in Figures 1 and 2, and the link J is bent to compensate for the lesser length of arm j . The opposite end of the link J is pivoted at j^3 , as shown best in Figures 10 and 11, to a gear wheel T , which, with other mechanism hereinafter described and including the friction disk M , is supported on a frame T' suspended rigidly on hangers t' from the left hand end. Gear T is mounted on stub-shaft t and meshes with a pinion U , fixed on the arbor u which, in turn, carries a gear u' . Gear u' meshes with the pinion m^3 fixed on the shaft m , which carried the friction wheel M' . The end of shaft m which carries pinion m^3 is journaled for rotation and slight gyration in a rigid element t^2 of hanger T' ,

as shown best in Figure 10, while the opposite end of said shaft is journaled in a swinging stirrup V suspended for oscillation on pin v , which is rigid with hanger T' .

By thus supporting the shaft m , friction wheel M' may be moved into or out of engagement with friction disk M through the oscillation of stirrup V on pin v . In practice, it is not necessary to actually move the friction wheel free from engagement with the friction disk, but, merely, to vary the pressure between said parts. In the embodiment of the invention now under discussion, this variance in pressure is governed by one of the stops O O' , and said stops are connected, for such operation, with the lower end of stirrup V through the medium of an equalizer W mounted for oscillation on a pin w which is rigid with the stirrup, as shown best in Figure 10.

85 The stops O O' are provided, and between them is adapted to operate the music sheet X , which, operating against said stops, serves to control the tracking device in a more simple manner than hereinbefore described. The stops O O' are fixed to the forward ends of levers o^2 and o^3 , respectively, which are pivoted on brackets o and o' , and with which are associated springs o^4 and o^5 , which serve the function of impelling stops O and O' toward one another.

90 Lever o^2 is connected through a link w^2 with the upper end of equalizer W , while lever o^3 is connected by a link w^3 with the lower end of equalizer W . As the result of 100 this connection, the positioning of a music sheet X between stops O and O' will cause them to be forced apart a distance equal to the width of the sheet, so that said stops will contact with the opposite edges of said sheet. During this operation, the engagement of the sheet against stop O' will place tension upon link w^3 , which will serve to rotate equalizer W and place link w^2 under tension for the purpose of moving stop O in an opposite direction from the movement of stop O' and for an equal distance. The pressure against stop O' , for the purpose of compensating for the difference in width of music sheets, will have a tendency to pull 110 friction wheel M' against friction disk M . However, after the sheet is in position, any tendency of said sheet to creep laterally in the direction of stop O would place link w^2 under compression and tend to rotate the 115 equalizer in a counter-clockwise direction. This rotation of the equalizer will, however, be opposed by the tension of the spring o^5 associated with stop O' , and the result will be that, instead of rotating the equalizer to 120 move stop O' against the tension of spring o^5 , movement will be imparted to stirrup V and friction wheel M will be moved in a direction away from the friction disk.

125 If it be assumed that the machine is oper- 130

ating to play a piece of music, i. e., that a music sheet is in engagement with trunnion D and that gear g' is operating to cause the travel of said sheet over the tracker to wind 5 the sheet upon the take-up roll, the spring within trunnion D will be forcing the music roll toward the right and impelling trunnion E, which cooperates with the opposite end thereof, against the finger i mounted on shaft 10 I. This will have a tendency to draw the link J toward the right, because of its connection through arm j with shaft I. However, when shaft c is rotating to operate the take-up roll, the sprocket and chain connection 15 l is operating to rotate friction disk M, and, by virtue of friction wheel M', which is in engagement with said disk, operates, through the gearing m^3, u', U and T, to draw said link J to the left in opposition to the 20 power of the spring d associated with trunnion D. In the normal operation of the parts, this is what occurs when the sheet is in correct position. In Figure 11, the relative position of the gearing is shown at a 25 point whereat link J is partially retracted. The retracting of link J is, of course, dependent upon the tight engagement of friction wheel M' with disk M, since, as soon as the traction between these parts fails to 30 operate, through the letting up of the pressure, wheel M' will slip, and the spring in trunnion D will exert itself and will force the music roll, which carries the music sheet, to the right in Figures 8 and 9.

35 It will thus appear that, as long as the music sheet is riding smoothly and in correct position over the tracker, a substantially even pressure will be imposed upon both stops O and O' and friction wheel M' will 40 be held tightly against disk M. As long as this state prevails, the disk will operate, through friction wheel M', to cause a steady retraction of link J and a correspondingly steady movement of the music sheet X to the 45 left. However, as soon as the sheet X, by virtue of such movement, begins to exert excess pressure on stop O, link w^2 will be under compression, with the result that the pressure of wheel M' against disk M will be 50 lessened and slipping will occur, bringing about retrograde movement of link J under the impulse of the spring in the trunnion D. There may thus be said to be two forces 55 counteracting each other, namely, the normal operation of the device, which serves, through the friction disk and cooperating connections, to move the entire music sheet to the left, against the tension of the spring trunnion D, while opposed to this operation 60 is the power of spring trunnion D for moving the sheet to the right. Stop O may be said to be the stabilizer of the forces, since varying pressures on said stop by the edge 65 of the sheet serves to place one force or the other into operation to maintain the aline-

ment. In view of the fact that this alignment is maintained merely by the changing of the pressure between the friction wheel and the friction disk, actual movement of stop O is unnecessary, since the slightest excess pressure exerted thereagainst by the music sheet will be immediately transmitted to produce a corresponding decrease in pressure between the friction disk and wheel, while a falling of the pressure between stop 70 O and the music sheet below normal will bring about a corresponding increase of pressure between the friction disk and wheel. The adjustment is of such nicety and the parts are so sensitive to varying pressures 75 that the slightest variation in pressure by the music sheet will be accompanied by a corresponding and instantaneous inverse variation of pressure between the friction disk and wheel, with the result that the music sheet will never become out of position, the slightest tendency in this direction being immediately compensated for. The high degree of sensitiveness is, in a measure, due to the ease with which stop O is free to 80 lessen the pressure which friction wheel M' normally exerts on friction disk M. In Figure 9, the friction wheel is shown as in engagement with the disk, and, in order to so engage, stirrup V is drawn at its lower 85 end toward said disk and appreciably out of vertical position. Accordingly, as soon as the force which maintains the stirrup out of its vertical position is released, the parts will, of course, immediately tend to gravitate 90 to bring the stirrup vertical. Thus, the action of stop O to decrease the traction between these parts is assisted by gravity, so that, in practice, really no power is required. This is an important feature, since the edge 95 of the music sheet is not actually required to do any work and is, accordingly, not subjected to wear, as would be the case if actual work were required by the edge of said sheet.

100 Moreover, through the employment of the equalizer, as in the previously described construction, slight variations in the width of the music sheet are compensated for and will not serve to throw the sheet out of alignment, as has heretofore universally been the case.

105 In the modified construction just described, means is also provided for moving stops O and O' free from engagement with the edges 110 of the sheet during the rewinding operation, and this means is in the form of a single link s , which is connected with the clutch operating lever h , passes through side wall A' of the casing, and is provided at its inner 115 end with a hook s^3 adapted to engage with the inner edge of lever o^3 . Thus, when lever h' is thrown to the right in Figure 8, link s will serve to draw stop O' to the right, and, through links w^3 and w^2 and 120

125 130 135 140 145 150 155 160 165 170 175 180

equalizer W, will bring about the movement of stop O to the left, where said stops will be entirely free from engagement with the edge of the music sheet during the subsequent rewinding operation. The mere act of returning the clutch into playing position will automatically release the stops and allow of their return, under the impulse of springs o⁴ and o⁵, to correct playing position where they will engage with the edges of the music sheet.

It will be apparent from the foregoing description of the embodiment of the invention illustrated in Figures 8 to 11, that it is much simpler in construction and more sensitive in its operation than the construction of the preceding figures, although either construction may be employed to great practical advantage over anything heretofore suggested in the art.

In Figures 12 and 13, I have illustrated in detail clutch mechanism between shaft c and the sprocket and chain connections l which drive the friction disk. This is a very simple form of clutch and operates with great efficiency. The structure consists in a collar 15 which is fixed upon shaft c by a set-screw 16. Upon collar 15 is rotatably mounted, by a screw 17, a small disk 18 against which the gear 19 is forced by a spring 20. Gear 19 is provided with a plurality of pockets or apertures 21, with which is adapted to cooperate a finger 22 mounted rigidly on the small disk 18.

As long as shaft c is rotated in a counter-clockwise direction, with reference to Figure 13, disk 18 will ride on the adjacent surface of gear 19 and, in its attempt to rotate, will force pin 22 tightly against the face of said gear, the end of said pin entering one of the pockets 21 and locking the parts together for relative movement. However, if, through inadvertence or otherwise, an attempt is made to rotate gear 19 in a clockwise direction from shaft c, the rolling action of the small disk 18 against the face of said gear will rotate pin 22 out of pocket 21, with which it cooperated, and gear 19 will remain idle. Thus, during the rewinding operation, gear 19 will remain idle and no movement will be imparted to the friction disk. In order to preclude the shifting of pin 22 into a position unnecessarily distant from the gear, disk 18 is provided with a notch 23 which cooperates with a stop 24 on sleeve 15 and serves to limit the rotation of the disk to the predetermined angular travel desired.

The foregoing clutch mechanism, while preferably used in carrying out the present invention, is not exclusive, as other clutch mechanisms may be employed if desired. The mechanism shown, however, is highly efficient and positive in its operation, and is preferred.

It is to be noted that while the friction wheel M' and the disc M are constantly in contact, the traction or pressure of the one against the other varies in accordance with the varying pressure of the sheet upon the edge guide, and this varying pressure is what causes and allows the wheel M' to rotate in one direction or the other.

It will be noted that the friction mechanism hereinbefore described constitutes a clutch.

Having thus fully described the invention, what I claim as new, and desire to secure by Letters Patent, is:

1. The method of automatically maintaining registration between the perforations of a music sheet and the air ducts of a tracker bar, which consists in mechanically varying pressure to preserve alinement without lateral deviation of the music sheet from its correct position. 80

2. A friction wheel arranged to constantly revolve in one direction, a cooperating friction wheel constantly in contact therewith, and means for varying the direction of rotation of the latter by relaxation or excess of pressure. 90

3. A constantly revolving friction wheel, a friction wheel for constant contact therewith, and means operable by variations of pressure without affecting the alinement of a note sheet for controlling the direction of rotation of the last-named friction wheel. 95

4. A constantly revolving friction wheel, a cooperating friction wheel, edge-contacting means, and an oscillatory member operatively connected with said means and movable to vary the pressure to cause the last-named wheel to revolve in one direction or the other. 100

5. A friction wheel, movable by variations of pressure to change the direction of rotation of said wheel, and means constantly in contact therewith for rotating said wheel in one direction. 105

6. A friction wheel, means affected by variations of pressure to change the direction of rotation of said wheel, and means operatively connected with the first-named means for maintaining permanent alinement of the note sheet. 110

7. A friction wheel, a cooperating revolute member constantly in contact therewith and means controlled by variations of pressure to change the direction of rotation of said wheel, said means being at all times in operative relation. 115

8. A friction wheel positively frictionally revolvable in one direction only, and non-pneumatic means affected by variations in pressure to change the direction of rotation of said wheel. 120

9. Sheet-centralizing means embodying constantly-in-contact revolute friction members. 125

10. Sheet-centralizing means embodying constantly-in-contact revoluble friction members, and a sheet-actuated compensator.

11. Sheet-centralizing means embodying 5 constantly-in-contact friction members and an oscillatory compensator operatively connected with one of said members.

12. Sheet-centralizing means embodying 10 constantly-in-contact friction members, sheet-positioning means embodying an oscillatory member and an oscillatory compensator carried by an oscillatory member of the sheet-positioning means.

13. Sheet-centralizing means, embodying 15 a constantly-revolving member, a friction wheel constantly in contact therewith and actuated thereby, and means whereby said friction wheel is caused to intermittently reverse its direction of rotation.

20. 14. Sheet-centralizing means embodying a constantly-revolving member, a friction member actuated thereby and constantly in contact therewith, and means whereby one of said members is caused to intermittently reverse 25 its direction of rotation.

15. Sheet-centralizing means embodying a friction member controllable in one movement by a music-spool spring.

16. Sheet-centralizing means embodying 30 constantly-in-contact revoluble friction members, and edge-guiding means operatively connected with and controlling the same.

17. Sheet-centralizing means embodying 35 compensating means, sheet-contacting means operatively connected therewith, and a revoluble friction member operatively connected with the compensating means.

18. Sheet-centralizing means embodying 40 oscillatory compensating means, and sheet-contacting means operatively connected therewith.

19. Edge-contacting means, an oscillatory compensator operating in unison therewith, and friction means operated thereby.

45. 20. Edge-contacting means, an oscillatory compensator operating in unison therewith, an oscillatory support for said oscillatory compensator and upon which the same is mounted, and friction means operated thereby.

50. 21. A trackerbar, edge guides having portions protruding beyond said bar, and pivotally mounted upon the other side of said bar on stationary supports, revoluble friction means, and connections between said edge guides and friction means.

55. 22. A trackerbar, edge guides having portions extended beyond the said bar, said edge guides pivotally mounted on fixed supports, friction means and connections between said friction means and the said edge guides, said connections being disposed between the pivots of said edge guides and said bar.

60. 23. A trackerbar, edge guides pivotally

mounted on fixed supports and having their free ends extended beyond the bar, friction means, and means connected with said edge guides between their pivots and free ends and connected with said friction means. 70

24. Friction means, the members of which are constantly in contact with each other one member of which moves constantly in one direction during forward movement of the sheet, and another member movable in either direction and controlled in its movements by pressure of the note sheet while maintaining its centralized position. 75

25. Friction means movable in one direction only by friction, edge contacting means, 80 and intermediate means for determining the direction of rotation of one of the friction members by variation of pressure exerted by said edge contacting means.

26. A friction wheel movable in one direction only by friction, controllable as to its direction of rotation by pressure thereupon. 85

27. A friction wheel movable in one direction only by friction, and means whereby it is automatically controlled in its direction 90 of rotation by variations in pressure while the note sheet is maintained in position.

28. A friction wheel movable in one direction only by friction, and oscillatory pressure-exerting means for automatically controlling the direction of rotation of said friction wheel. 95

29. A friction wheel, means for constantly revolving the same in one direction, a co-operating friction wheel, a sector actuated 100 thereby, an endwise movable music spool, and connections between the said sector and spool for controlling the movement of the latter in either direction, said cooperating wheel being rotatable in one direction by the first-named wheel, and a spring for rotating it in the opposite direction.

30. Cooperating friction wheels one of which is revolved in one direction only by friction, a sector operated by one of said 110 wheels, an endwise-removable music spool, and variable pressure means controlled by the music sheet for controlling the direction of rotation of one of said wheels.

31. Cooperating friction wheels one of which is revolved in one direction only by friction, a sector actuated by one of said wheels, an endwise-movable music spool actuated by the sector, and means contacting with the sheet for controlling the movement 120 of one of said friction wheels.

32. Mechanical means and connections for controlling endwise movement of a music spool, cooperating friction wheels controlling said spool-moving means, edge-contacting means for controlling the movements of one of said wheels, and a spring acting in opposition to said spool-moving means. 125

33. In mechanical means for moving a spool endwise in either direction, friction 130

means for moving it in one direction and non-friction means for moving it in the other direction.

34. Rotatable friction means for causing 5 a music spool to move endwise, said rotatable means rotated in one direction by friction means and rotating in the opposite direction by non-friction means.

35. Rotatable friction means for causing 10 a music spool to move endwise, said rotatable means rotated in one direction by friction means and rotating in the opposite direction by non-friction means, and means contacting with the edge of a note sheet 15 for controlling said rotating means.

36. Rotatable friction means one member of which is moved in one direction only by friction, one member of which moves constantly in one direction and the other alternately in opposite directions, combined with 20 variable pressure means for imparting one of the motions to such member.

37. Rotatable friction means, one member of which moves constantly in one direction and the other alternately in opposite directions, combined with non-friction variable pressure means for imparting one of the motions to such member.

38. In a web guiding mechanism, rotatable friction means for positioning said web rotating in either direction while in constant contact with a rotatable friction disc operating in one direction.

39. In a web guiding mechanism, rotatable friction means for positioning said web rotating in either direction while in constant contact with a rotatable friction disc operating in one direction, and non-friction means for rotating said rotating means in 40 one direction.

40. In a web guiding mechanism, rotatable friction means for positioning said web rotating in either direction while in constant contact with a rotatable friction disc operating in one direction, and edge contacting means for controlling said rotating means.

41. A trackerbar, a music spool and a take-up roll, means for giving endwise movement to the music spool while a note sheet is being wound therefrom upon the take-up roll, and means whereby the note sheet is maintained against lateral movement in its passage over the trackerbar.

42. A trackerbar, a music spool and a take-up roll, friction means for giving endwise movement to the music spool while a note sheet is being wound therefrom upon the take-up roll, and means whereby the note sheet is maintained against lateral movement in its passage over the trackerbar.

43. A trackerbar, a music spool and a take-up roll, means for giving endwise movement 65 to the music spool while a note sheet is being

wound therefrom upon the take-up roll, means whereby the note sheet is maintained against lateral movement in its passage over the trackerbar, and means controlled by the note sheet for controlling the music 70 spool moving means.

44. A trackerbar, a music spool and a take-up roll, means for giving endwise movement to the music spool while a note sheet is being wound therefrom upon the 75 take-up roll, means whereby the note sheet is maintained against lateral movement in its passage over the trackerbar, and edge contacting means for controlling the spool-moving means.

45. In a tracking device, the combination of two edge guides, each of which is pivoted rearwardly of the trackerbar, and each of which projects forwardly to a point forward of the trackerbar, friction means for controlling the lateral positioning of a note sheet, and connections between the friction means and the edge guiding means independently and individually.

46. In a tracking device, the combination 90 of two edge guides, each of which is pivoted rearwardly of the trackerbar and each of which projects forwardly to a point forward of the trackerbar, friction means for controlling the lateral positioning of a note 95 sheet, and connections between the friction means and the edge guiding means individually, said connections cooperating with the edge guides intermediate their free ends and their points of pivoting.

47. In a tracking device, the combination of two edge guides, each of which is pivoted, on fixed supports, rearwardly of the trackerbar and each of which projects forwardly to a point forward of the trackerbar, friction means for controlling the lateral positioning of a note sheet, and connections between the friction means and the edge guiding means individually.

48. In a tracking device, the combination 110 of two edge guides, each of which is pivoted rearwardly of the trackerbar and each of which projects forwardly to a point forward of the trackerbar, friction means for controlling the lateral positioning of a note 115 sheet, and connections between the friction means and the edge guiding means individually, said connections embodying means for compensating for different widths of note sheets.

49. In a tracking device, friction clutch mechanism for controlling the lateral positioning of a note sheet, said mechanism embodying a plurality of cooperating friction clutch elements, members contacting 125 with the opposite edges of the sheet and movable thereby for causing the sheet to be moved in opposite directions when inserting the music roll, and operative connections between said members and the friction 130

clutch elements, said connections including a compensating equalizer for accommodating sheets of different widths.

50. In a device of the character described, 5 a trackerbar, a music sheet associated therewith, mechanism for causing the music sheet to travel over the trackerbar, a friction clutch, one member of which is mounted to normally gravitate free from engagement 10 with the other clutch member, in combination with means for normally maintaining the clutch members in tight engagement with one another, and means, controlled by physical contact with the music sheet, for varying 15 the pressures between such clutch members, whereby the music sheet automatically controls its positioning longitudinally of the tracker through its automatic control, the gravitating clutch member serving to 20 render said control highly sensitive to the slightest tendency of the music sheet to move laterally.

51. A clutch member embodying driving and driven parts, and means mounted on 25 the driving part and operated by the driven part for positively locking the parts together when the driving part is rotated in one direction and automatically releasing the driven part when the driving part is 30 driven in the opposite direction.

52. A friction member constantly movable in one direction, a cooperating friction member moved thereby in one direction, and independent means for moving the said 35 member in the opposite direction.

53. The method of automatically maintaining registration between the perforations of a music sheet and the air ducts of a tracker-bar, which consists in maintaining 40 constant contact of relatively-movable friction members and by variations of pressure preventing perceptible lateral deviation of the music sheet.

54. Cooperating revolute members one of 45 which is revolute in one direction by contact with the other member and in the other direction by decrease of frictional contact of said members.

55. A friction member, and a cooperating 50 friction member operable in one direction by direct pressure and contact with the first-named member and operable in the opposite direction by slippage or decreased frictional contact of the two members.

56. A revolute friction member, and a 55 cooperating revolute friction member, the two being in substantially constant contact, the one being revolute in one direction by frictional contact of the two and in the opposite direction by non-friction means.

57. A revolute friction member, and a 60 cooperating revolute friction member, the two being in substantially constant contact, the one being revolute in one direction by frictional contact of the two and in the op-

posite direction by non-friction means made operable upon decrease of such frictional contact.

58. Constantly-operating means controlled by the movement of the note sheet for preventing lateral deviation of said sheet. 70

59. Constantly - operating mechanical means controlled by the movement of the note sheet for preventing lateral deviation of said sheet. 75

60. Constantly - operating friction means controlled by the movement of the note sheet for preventing lateral deviation of said sheet.

61. In a tracker mechanism for player 80 pianos, the combination with a tracker bar and rolls supporting a music sheet, of a lever adapted to control the transverse movement of one of the aforesaid members to maintain registration between the music sheet and 85 tracker bar, a rotatable member connected with and operating said lever, a clutch controlling the movement of said rotatable member, means for driving said clutch, guiding fingers adapted to engage the music 90 sheet in passage over the tracker bar, and means connected with said guiding fingers adapted to operate said clutch.

62. In a tracker mechanism for player 95 pianos, the combination with a tracker bar and rolls supporting a music sheet, of a lever adapted to control the transverse movement of one of the aforesaid members to maintain registration between the music sheet and 100 tracker bar, a rotatable member pivotally connected with and operating said lever, a spur gear secured to said rotatable member, a train of gears connected with said spur gear, a clutch member operatively connected with said train of gears, a driving clutch 105 member cooperating with the aforesaid clutch, a lever adapted to bring said clutch members into operating contact, guiding fingers adapted to engage the music sheet in 110 its passage over the tracker bar, and means connecting said fingers with said clutch operating lever.

63. In a tracker mechanism for player 115 pianos, the combination with a tracker bar and rolls supporting a music sheet, of a lever adapted to control the transverse movement of one of the aforesaid members to maintain registration between the music sheet and 120 tracker bar, a rotatable member pivotally connected with and operating said lever, a spur gear secured to said rotatable member, a train of gears connected with said spur gear, a clutch member operatively connected with said train of gears, and supported on a movable spindle, a driving clutch 125 member rotatably supported on a fixed journal and adapted to be engaged by the aforesaid clutch member to effect the rotation of said train of gears, a lever pivotally supported and having one end operatively 130

- engaging the movable spindle, a pair of guiding fingers arranged one at each side of the music sheet and spring held in contact with the edge of the sheet, a rod connecting the lever controlling the clutch spindle with one of said fingers and adapted upon the outward movement of the finger to bring the clutch members into operating contact to rotate the train of gears and to operate the lever controlling the alinement of the music sheet and tracker bar, and a rod connecting the other of said guiding fingers with the lever controlling the clutch spindle and adapted to release the clutch, and means for effecting the transverse movement of the member effecting the registration between the music sheet and tracker bar.
64. In a tracker mechanism for player pianos, the combination with the tracker bar and rolls supporting a music sheet, of pressure means for moving one of said members transversely, a lever engaging said movable member and adapted to control the transverse movement thereof, a rotatable member pivotally connected with said lever and adapted to swing it upon its pivot, a gear mechanism for swinging said rotatable member, a clutch, a driving mechanism, a clutch interposed between said driving mechanism and said gear mechanism, a pair of guiding fingers arranged one at each side of the music sheet engaging same as it passes over the tracker bar, means connecting one of said fingers with said clutch mechanism and adapted to release the same, and means connecting the other of said fingers with the clutch mechanism and adapted to move the clutch into operating contact, means for rewinding the music roll, and means for moving the contact fingers out of engagement with the music sheet during the rewinding.
65. In a tracker mechanism for player pianos, the combination with a stationary tracker bar and a transversely movable music roll, of pressure means for moving said music roll in one direction, a lever member adapted to move the music roll in the opposite direction, a pivotal arm connected with said lever member and adapted to swing said lever to move the roll, a gear mechanism connected with said pivotal arm, a clutch connected with said gear mechanism, means for driving said clutch coincident with the operation of unwinding the music roll, guiding fingers arranged upon the tracker bar, means connected with one of said guiding fingers for releasing the clutch, and means connected with the other of said guiding fingers for engaging the clutch.
66. In a tracker mechanism for player pianos, the combination with the tracker bar and rolls supporting the music sheet, of a lever adapted to control the transverse movement of one of the aforesaid members to maintain registration between the music sheet and tracker bar, a pivotal member operatively connected with said lever, a gear mechanism operating said pivotal member, a clutch arranged in said gear mechanism having a movable member, a lever adapted to move said clutch into operating engagement, a pivotal arm supported on the outer end of said lever, a pair of pivotal guide fingers supported from the tracker bar and engaging the sides of the music sheet, a rod connecting one of said guide fingers with the upper end of the pivotal member on the clutch lever, and a rod connecting the lower end of the pivotal member on the clutch lever with the other guiding finger.
67. In a tracker mechanism for player pianos, a frame, a winding roller supported at the bottom of the frame, a tracker bar supported intermediate of the height of the frame, a music roll supported at the top of the frame, a driving shaft journaled intermediate between the supporting shafts for said rollers, a sprocket wheel loosely mounted on said driving shaft and operatively connected with a sprocket wheel on the music roll shaft, said loose sprocket wheel having a laterally projecting tooth, a sleeve slidably mounted upon and rotating with the driving shaft and having at one end a tooth adapted to engage the tooth on said sprocket wheel and at the other end a spur pinion, a lever supported in the frame and operatively connected with said sleeve to slide it upon the driving shaft, a spur gear mounted upon the winding roller shaft and adapted to mesh with the pinion of said sleeve, a train of gears, a clutch mechanism arranged in said train of gears, a lever connected with said train of gears and operatively engaging the music roll shaft and adapted to move same longitudinally, and means operatively engaging the music sheet and adapted to control the operation of said clutch.
68. In a tracker mechanism for player pianos, the combination with a stationary tracker bar and frame support, of a longitudinally movable shaft arranged above said tracker bar, a music roll having one end supported upon said longitudinally movable shaft, a longitudinally movable spindle supporting the other end of said music roll, means operatively connected with said spindle to move same longitudinally in one direction, a lever pivotally mounted in the frame and engaging the outer end of the roll shaft, an arm connected with said lever, a swinging arm pivotally connected to the lever arm, a train of gears operatively connected to said swinging arm, a clutch member interposed in said train of gears, means for operating said train of gears coincident with the unwinding of the music roll, a pair of guiding fingers arranged one at each side of the music sheet and adapted to engage

the same in passage over the tracker bar, means operatively connecting said fingers to control said clutch to effect the longitudinal displacement of the music roll in either 5 direction to maintain its register with the tracker bar.

69. Constantly-operating means controlled by the movement of the note-sheet for pre-

venting lateral deviation of said sheet and operative by infinitesimal excess pressure. 10

In testimony whereof I affix my signature in the presence of two witnesses.
